PLASTIC SHEET MATERIAL

David Lyon, New Britain, Conn., assignor to Rowland Products Incorporated, Kensington, Conn., a corporation of Connecticut

Filed Aug. 12, 1963, Ser. No. 76,188

Term of patent 14 years

(Cl. D87—3)

FIG.1

The design repeats in a horizontal direction and a full width is shown vertically.

I claim:

The ornamental design for a plastic sheet material, as shown and described.
